UNITED STATES PATENT OFFICE.

JUNIUS EMMETT MAYO, OF BELVIDERE, ILLINOIS, ASSIGNOR TO NATIONAL SEWING MACHINE CO., OF BELVIDERE, ILLINOIS, A CORPORATION OF ILLINOIS.

HANGER FOR ELECTRIC LAMPS.

984,687.

Specification of Letters Patent.

Patented Feb. 21, 1911.

Application filed January 28, 1907. Serial No. 354,374.

To all whom it may concern:

Be it known that I, JUNIUS E. MAYO, a citizen of the United States, residing at Belvidere, in the county of Boone and State 5 of Illinois, have invented certain new and useful Improvements in Hangers for Electric Lamps, of which the following is a full, clear, and exact specification.

This invention relates to that class of 10 hangers for suspending electric lights from an overhead support, in which provision is made for lowering the lamp from its elevated position and automatically cutting it out of the circuit without opening the circuit 15 through other lamps in the circuit, and it has, for its primary object, to provide an improved and efficient construction of lamp hanger of this character, which shall be appropriate for use with a metallic cable for 20 raising and lowering the lamp supporting member of the hanger without danger to the operator.

Another object of the invention is to provide an improved form of joint connection 25 between the hanger proper and the pulley bracket, whereby the hanger proper will be given freedom of movement in all directions without interfering with the free run of the cable.

With a view to the attainment of these 30 ends, and the accomplishment of certain other objects which will hereinafter more fully appear, the invention consists in certain features of novelty which will now be 35 described with reference to the accompanying drawings and more particularly pointed out in the claim.

In said drawings Figure 1 is a vertical 40 sectional view, partly in elevation, of a lamp hanger with the pulley bracket thereon, showing the lamp supporting plunger locked in place with the lamp in circuit. Fig. 1^a is an enlarged detail view showing the manner of connecting the conductor to 45 one of the contact rings on the plunger. Fig. 2 is an enlarged side elevation of the pulley bracket showing the same open. Fig. 3 is a vertical sectional view of the lamp bracket showing the plunger lowered with 50 the lamp cut out. Fig. 4 is a transverse sectional view on line 4—4, Fig. 1. Fig. 5 is a similar view on line 5—5, Fig. 1. Fig. 6 is a similar view on line 6—6, Fig. 1. Fig.

7 is a side elevation with the casing broken away showing the plunger in place with 55 the lamp in circuit. Fig. 8 is a detail perspective view of the plunger and connected parts on an enlarged scale. Fig. 9 is a detail side elevation of the cut out switch showing also the connections between one 60 of the conductors and the upper contact ring, and Fig. 10 is an enlarged detail view of the opposite member of the cut out switch showing also the connection between the other conductor and the lower contact ring. 65

This invention is designed more especially as an improvement upon the hanger for electric lamps shown in my U. S. Patent No. 614,484 of November 22, 1898, and to which reference may be had for a more detailed 70 description of parts which are common to both devices.

In my former construction it will be seen that the lamp supporting plunger marked K in my former patent and 1 in my present 75 invention, is directly in circuit with the lamp and the hoisting rope which is connected directly to the plunger cannot, of course, be composed of anything excepting a material of an insulating or non-conducting character. Formerly this hoisting member has been composed of hemp or cotton 80 rope, but even this becomes saturated with moisture and in time affords a fair passage for the current which not only is thereby 85 communicated to the body of the operator handling the hoisting rope, but to other parts of the device, and through it to the building. Furthermore, the use of hoisting 90 rope composed of cotton, hemp or other vegetable fiber, is objectionable for the reason that these ropes are desirably of small diameter and are liable to break and permit the lamp to fall.

In my present invention the hoisting rope 95 which is shown at 2 may be composed of a metallic cable. Its lower end is secured by nut 3 to the upper end of the plunger 1 and this plunger is provided with a locking device 4 of the usual or any suitable construction adapted to engage in a recess 5 in the inverted socket piece 6, all as described in the aforesaid patent. The upper end of the socket piece 6 is supported in a hood 7 on a suitable block 8 of insulation 100 and its lower end is provided with an insu-

lating sleeve or jacket 9 on which are mounted two conducting plates or rings 10—11, the upper ring 10 being mounted on a flange or enlargement 12 of the insulating sleeve 9 and is of greater diameter than the lower ring 11 so that the elastic contact clips 13—14 which are adapted to engage with rings 10—11 respectively, and will not engage the wrong ring. Any suitable number 5 of these contacts 13—14 may be employed. In the present exemplification of the invention two of each are used, those for the upper ring 10 being longer than those which engage the lower ring 11. These contact 10 clips are mounted upon the plunger 1 and are insulated therefrom by means of a sleeve or jacket 15 of any suitable insulating material. The clips 13 have their lower ends connected to a conducting ring 16 and the 15 clips 14 are secured to a similar ring 17 but which is preferably of larger diameter than the ring 16 and is mounted upon an enlarged shoulder of the insulating sleeve 15 so that the clips 14 will not touch the ring 20 16 but will pass thereby and engage their proper contact ring 11 above. The lips 13, 14 being arranged in different vertical planes, the lip 13 will pass a ring 11 as the plunger is being inserted into or withdrawn 25 from the socket and will engage only their respective ring 10.

18—19 are the main line conductors which pass into the hood 7 through suitable entrances such as 20 containing insulating linings 21. The conductor 18 is secured to binding post 22 and this post is connected to the lower contact ring 11 by a conductor 23 which is in the form of a thin plate or strip and passes through the flange or shoulder 30 46—47 respectively of a pulley casing or bracket which are connected together by hinge 48 and adapted to fold together and inclose the pulley 42 and that portion of the cable immediately contiguous to the pulley, thereby affording a convenient means for readily placing the cable in position on the pulley as well as mounting the lamp hanger proper with its trunnions 43 in the pulley bracket. The upper side of the pulley bracket on one of the members 46—47 is provided with an elongated sleeve or bearing 49 which receives journal 50 looped downwardly from a ceiling plate 51 adapted to be secured to the ceiling or any other suitable overhead support in the usual or any appropriate manner, the journal 50 being at an angle to the trunnions 43 so that the two together constitute an efficient joint connection for the hanger, permitting freedom of movement in directions at substantially right angles to each other, while the lamp itself as it hangs from its usual supporting pulley 52 on the lower end of the plunger 1 is capable of rotating with said plunger on a vertical axis without interfering with the electrical connections.

70 mounted upon a similar block of insulation 38 on the side of the socket piece 6, the binding screw 22 before described serving also to connect the conductor 18 to the switch spring 37.

75 Mounted in the side of the socket piece 6 and directly behind the spring 37 is a stud 39 adapted to project into the cavity of the socket piece and having a head 40 at its outer end to hold it against inward displacement. This stud 39 is composed of insulation or nonconducting material or any other provision may be made for preventing the stud from conducting the current from the spring 37, so that when the plunger 1 80 is forced into the socket and engages with the stud 39 the cut-out switch members 35—36 will be forced out of engagement with each other and the current will be compelled to pass through the lamp without any 85 of the current being communicated to the plunger 1 or metallic parts of the device excepting the regular electric conductors. When the plunger 1 is withdrawn, the spring 37 forces the stud 39 inwardly and the contacts 35—36 are brought together for completing the circuit or shunting it around the lamp.

90 The upper side of the hood 7 is provided with a hollow stem 41 through which the cable 2 passes upwardly over a pulley 42. The sides of this stem 41 are formed with trunnions or pivots 43 which are journaled in bearings 44—45 produced in two halves 95 46—47 respectively of a pulley casing or bracket which are connected together by hinge 48 and adapted to fold together and inclose the pulley 42 and that portion of the cable immediately contiguous to the pulley, thereby affording a convenient means for 100 readily placing the cable in position on the pulley as well as mounting the lamp hanger proper with its trunnions 43 in the pulley bracket. The upper side of the pulley bracket on one of the members 46—47 is provided with an elongated sleeve or bearing 49 which receives journal 50 looped downwardly from a ceiling plate 51 adapted to be secured to the ceiling or any other suitable overhead support in the usual or 105 any appropriate manner, the journal 50 being at an angle to the trunnions 43 so that the two together constitute an efficient joint connection for the hanger, permitting freedom of movement in directions at substantially right angles to each other, while the lamp itself as it hangs from its usual supporting pulley 52 on the lower end of the plunger 1 is capable of rotating with said plunger on a vertical axis without interfering with the electrical connections.

110 In order that those skilled in the art may understand the invention an exemplification thereof has been thus specifically described, but

What I claim as new and desire to secure by Letters Patent is:—

In a device for the purpose described, the combination with an apertured socket provided with two conducting rings of different diameters coaxially arranged and insulated therefrom and from each other, said rings being adapted to have conductors from the main line of an electric lighting circuit secured thereto, of a plunger for mounting an electric lamp, a wire cable secured to said plunger and movable through the aperture in said socket for lowering and raising said lamp, and contacts for connection with the terminals of the lamp, said contacts being

mounted on said plunger at different distances from the axis thereof and insulated therefrom and from each other, said contacts being adapted by their relative positions to be moved into and out of contact with said conducting rings by the movement of said plunger.

In testimony whereof I have signed my name to this specification, in the presence of two subscribing witnesses, on this 24th day of January A. D. 1907.

JUNIUS EMMETT MAYO.
